UNITED STATES PATENT OFFICE.

JORGEN OLSON, OF CASHTON, WISCONSIN.

DOUBLE-SEAMING STAKE.

1,337,466.

Specification of Letters Patent. Patented Apr. 20, 1920.

Application filed June 10, 1919. Serial No. 303,105.

To all whom it may concern:

Be it known that I, JORGEN OLSON, a citizen of Norway, residing at Cashton, in the county of Monroe and State of Wisconsin, have invented certain new and useful Improvements in Double-Seaming Stakes, of which the following is a specification.

This invention relates to metal bending, and more especially to the combined operation of bending and curving; and the object of the same is to produce a tinner's stake by means of which a round article can be double seamed with the proper tool.

A further object is to shape the seaming head so that it will enter the rather small mouth of a utensil having a breast, such as a tea kettle, but the active face of this head is shaped so as to facilitate double seaming when the work is in place thereon.

Another object is to provide the tool with a detachable and adjustable support so that a cylindrical piece of work can be mounted thereon.

Details are set forth in the following specification and claims, and reference is made herewith to the drawings, wherein:

Figure 1 is a perspective view showing this device as employed for supporting a cylindrical piece of work such as a can.

Fig. 2 is an elevation showing this device employed in the act of double seaming a tea kettle.

Fig. 3 is a detail of an extra seaming head having a working face of larger curvature.

Cylindrical work is typified herein by the can C shown in Fig. 1, while work with a contracted mouth is typified by the tea kettle T shown in Fig. 2. In both these pieces of work the bottom is applied by a seam S, and D designates the same seam after it has been given its second bend so as to produce a double seam. The present invention is a tinner's stake with attachments, whereby a tinner having the ordinary tools can double seam work of either class.

Coming now to the details of the present invention, the numeral 1 in the drawings designates a work bench having a socket 2 into which is inserted the spur 3 at the inner end of an arm 4 which is possibly three feet long and projects out horizontally beyond the bench as shown. Carried by its outer end is an upstanding seaming head 5 whose lower end may have a pin 6 seated in a socket 7 in the arm, but whose upper end is widened and

arched, the face 8 being also beveled inward as best seen in Fig. 2, and the arch or curvature being such as is useful on the smallest size of work to be treated. It is thus possible to have this head removable from the arm so that one of larger curvature, as seen in Fig. 3, can be substituted, but a simpler arrangement would be to have two complete tools whereof one has a rather small head and the other a rather large head, then either could be used according to the requirements of the case, and the head in each tool would be fastened to the arm.

The numeral 15 designates the head of a support, also preferably having a comparatively narrow body and a widened upper end, but the active face 16 of this head, while curved on substantially the same arc as the face of the seaming head, is flat transversely rather than being inclined or beveled. The lower end of the support is forked as shown at 14, and the fork arms pass astride the main arm 4, a set screw 13 being passed through one of said fork arms for purposes of adjustment.

A screw bolt 12 is extended through the head 15 directly above the forked arms of the same and is adapted for strengthening the arms and preventing the same from cracking under the strain of the screw 13.

In the use of this device on a can or other plain cylindrical work as indicated at C in Fig. 1, the support is applied to the arm and properly adjusted, and then the can is slipped over the seaming head and the support, and the seam formed first as at S and then as at D. In the use of this tool in connection with a kettle T having a contracted mouth as indicated in Fig. 2, the mouth is inserted over the seaming head whose peculiar shape permits it to enter a comparatively small mouth, and then the work is passed over the arm 4 until the bottom of the tea kettle T or other object lies against the end of the arm and the outer side of the head 5. The work is then borne down onto the active face 8, and the bottom is first seamed onto the body thereof, as indicated at S, and then double seamed as indicated at D. It may not be necessary to use the support in this case. Or, it is quite possible to provide the outfit with a plurality of supports of different sizes, and use that which fits most accurately to the work being handled. Still, the provision of the fork 14 and set screw 13 in

the support shown, renders it adjustable and, therefore, useful on work of a variety of sizes.

Having thus described the invention, what 5 is claimed as new is:

1. A device of the class described including an arm having attaching means, a seaming head carried by the arm and having its outer portion arched, the outer face of said 10 seaming head being beveled inwardly, and a second head carried by said arm in spaced relation to said first named head, said second named head being adjustable on said arm and having its outer face disposed in 15 the horizontal plane of the outer face of said first named head.

2. A device of the class described including a horizontal supporting arm, a seaming head extending from the outer end portion of said arm, the lower end of said head being relatively narrow and the upper end being widened and extended transversely of the said arm and having a curved active face beveled toward the inner end of the arm, and a support adjustably connected at 25 its lower end to said arm and having its upper end widened and extended beyond the sides of said arm, said support being arranged in spaced parallel relation to said seaming head.

In testimony whereof I affix my signature.
JORGEN OLSON. [L.S.]
